MARY W. WELTY, OF NEW YORK, N. Y.

Letters Patent No. 99,380, dated February 1, 1870.

IMPROVEMENT IN SHIELD FOR SEWING-MACHINES.

The Schedule referred to in these Letters Patent and making part of the same.

To all whom it may concern:

Be it known that I, Mrs. MARY W. WELTY, of the city, county, and State of New York, have invented a new and improved Sewing-Machine Shield; and I do hereby declare that the following is a full, clear, and exact description thereof, which will enable others skilled in the art to make and use the same, reference being had to the accompanying drawings, forming part of this specification.

The object of this invention is to provide a shield-attachment to sewing-machines, by which the fabric to be sewed will be protected from the oil of the journals, and from injury by contact with the machinery, and which will, at the same time, form an extension and continuation of the cloth-plate of the machine, to let the fabric move smoothly over it.

Heretofore, several forms of shield-attachments have been proposed; but the same were either secured upon or under the feed-plate by projecting screws or other devices. They became thereby more of a hindrance to than a support of the fabric, and fulfilled merely the object of protecting the fabric from the oil or mechanism of the machinery.

My present invention consists, chiefly, in providing ears or lugs on the front end of the shield, such ears catching over and under the cloth-plate, so that they hold the shield in line with the cloth-plate, and cause it, therefore, to form a smooth continuation of the latter.

In the accompanying drawings—

Figures 1 and 2 are side views of two forms of my improved shield.

Figure 3 is a perspective view of the same.

Similar letters of reference indicate corresponding parts.

A, in the drawing, represents the shield. It is made of sheet-metal or other suitable material, of such form that it will fit the several kinds of sewing-machines

which are in use. Its shape will have to be varied, to adapt it to the various machines. In all cases, it forms first a horizontal backward projection, *a*, of the shield, and is then carried up, to hold the fabric away from the machinery.

On the front end of the shield, near the sides, incisions are made, which produce ears *b* and *c*. The latter are bent downward, and pass under the cloth-plate *B*, and the ear *b* above the plate, so that they retain the shield itself in line with the plate, as shown, causing it to be a smooth prolongation of said plate.

The ears *b* may also be soldered, or otherwise secured, separately, to the shield, and will then serve the same purpose as those which are formed by the incisions.

On the upright portion *d* of the shield is either secured a screw-clamp, *e*, to fasten it to an upright standard of the machine, or there are perforated lugs, *f*, to fit upon horizontal arbors or screws that project from the machine. In the latter case, wedges, *g*, screws, cams, or levers, are required to lock the shield.

The form of shield represented in figs 1 and 3 is adapted to the Willcox & Gibbs sewing-machine, while that shown in fig. 2 fits the Wheeler & Wilson machine.

I do not claim nor confine myself to any peculiar form of shield, nor device for fastening the same to the sewing-machine; but, having thus described my invention,

I do claim, and desire to secure by Letters Patent—

A sewing-machine shield, provided with the ears *b* *c* at its front end, the said ears fitting the edge of the cloth-plate of the machine, to hold the shield in line with the same, as set forth.

MRS. MARY W. WELTY.
